UNITED STATES PATENT OFFICE

JAMES E. CUFF, OF CHICAGO, ILLINOIS, ASSIGNOR TO AMERICAN FLYER MFG. CO., OF CHICAGO, ILLINOIS, A CORPORATION OF ILLINOIS

DESIGN FOR A TENDER FOR TOY LOCOMOTIVES

Application filed October 8, 1929. Serial No. 32,975. Term of patent 7 years.

To all whom it may concern:

Be it known that I, JAMES E. CUFF, a citizen of the United States, residing at Chicago, in the county of Cook and State of Illinois, have invented a new, original, and ornamental Design for Tender for Toy Locomotives of which the following is a specification, reference being had to the accompanying drawing, forming part thereof.

The figure is a perspective view of my improved design.

I claim:—

The ornamental design for tender for toy locomotives, as shown.

JAMES E. CUFF.
